TYPE-WRITER CARRIAGE-RETURN MECHANISM.

1,209,115.

Specification of Letters Patent. Patented Dec. 19, 1916.

Application filed March 3, 1916. Serial No. 81,895.

To all whom it may concern:

Be it known that I, EDUARDO CASTAÑEDA, a citizen of Mexico, residing at Monterey, in the State of Nuevo Leon, in the Republic of Mexico, have invented certain new and useful Improvements in Type-Writer Carriage-Return Mechanisms; and I do hereby declare the following to be a full, clear, and exact description of the invention, 10 such as will enable others skilled in the art to which it appertains to make and use the same, reference being had to the accompanying drawings, and to letters or figures of reference marked thereon, which form 15 a part of this specification.

My invention relates to carriage return mechanisms for attachment to typewriting machines, and has for its object to effect the return or movement of the carriage to and 20 fro by a short movement of a lever, key, or the like, for the purpose of returning the carriage to position for writing a new line, of reciprocating the carriage quickly to facilitate the reading of matter already 25 written, of setting the carriage at any desired point along the line, or of stepping the carriage forward, in lieu of actuating the usual letter spacing bar.

In order to maintain a short movement of 30 the lever, key, or other actuator, I provide a planetary mechanism for taking up the flexible connection connected to the carriage.

In order that my invention may be fully understood, I have shown my invention applied to a well known typewriter in the accompanying drawings, wherein like parts are similarly designated, and in which—

Figure 1 is a plan view of so much of a typewriter as is necessary to illustrate my 40 invention, the carriage return mechanism being shown in plan; Fig. 2 is a side elevation of the lever mechanism at the right hand side of the machine; Fig. 3 is a section on line 2—2, Fig. 2. Fig. 4 is as elevation of the mechanism at the left hand of 45 the carriage for actuating the escapement release. Fig. 5 is a side elevation thereof; Fig. 6 is a modification of Fig. 3, and Fig. 7 is a plan view of one form of supporting 50 or frame plate.

The lever mechanism at the right hand side of the machine comprises any suitable form of frame-plate 1, Fig. 7, shaped to conform to the machine to which the mech-

anism is to be applied. In the mechanism 55 herein shown, the frame-plate of sheet metal is provided with a rectangular slot 2, adapted to take around a bar *a* forming part of the typewriter, and is also provided with a hole for the reception of a bolt *b* also 60 forming part of the typewriter.

The bar *a* is provided with a nut *c* by means of which and the bolt *b* the plate is held in position on the typewriter. The base plate is provided with an inwardly 65 bent shoulder or stop 3 for the arcuate rack, and an outwardly bent stop 4 adjacent thereto for the actuating lever. This plate has an upright extension 5, and a lateral, substantially horizontal extension 6 70 forming a continuation of a portion 7 bent at right angles to the portion 5. The portions 5 and 7 are substantially perpendicular to the base 1. Mounted in the upright portion 5 is a shaft or bolt 8, Fig. 3, and on this 75 bolt is placed a sleeve 9, and a rack 13, both held between a washer 10, adjacent the bolt head, and a nut 11 on the end of the bolt, said nut having a collar or bearing 12.

On the bolt 8 is placed an arcuate rack 80 13; the forked ends 14 of a lever 15 also pivot around the bolt, and between the portion 5 of the base-plate and on the right hand fork end 14 is placed a coil-spring 16. Mounted on the fork arms 14 of lever 15 85 are a pinion 17 and a cord pulley 18 rigidly connected together. One end of the coil-spring 16 hooks over one of the fork arms 14, as shown at 19, Fig. 2. On the portion 5 of the frame plate 1 are mounted two 90 guide pulleys, 20 and 21, between which is guided the flexible connection or cord 22 to a horizontal pulley 23 mounted on the horizontal frame extension 6. This frame extension 6 is provided with a stationary 95 cord guide 24 having an eye or hook end 25, more clearly shown in Fig. 2; the cord then passes in front of the carriage and is detachably connected by an eye 26 to a headed pin 27 on the attachment, on the 100 left hand end of the carriage. This attachment comprises an arm 28 secured to the side *d* of the carriage frame by one of the screws *e* (Fig. 4) already existing in the typewriter.

Pivoted on a screw 29 in the end of the arm 28 is a lever 30 having an end 30^a bent at substantially right angles thereto.

- Loosely mounted on the collar *f* of the platen handle, which handle has a slight amount of longitudinal movement, is a sleeve 31, and for convenience of applying it to existing machines, this sleeve is provided with a hinge 32 and a pair of lugs passing through the lever 30 and held in place therein by a nut 34, a small cotter pin, or equivalent device.
- On the portion 30^a of the lever 30 is mounted the pin 27 to which the cord is detachably connected, and also an escapement disengaging lug in the form of a lever 35 whose nose 36 is arranged to engage the escapement release button *g* lever, or the like, on the carriage. This button, lever, or the like effects the disengagement of the carriage rack and escapement mechanism of the typewriter so as to permit the carriage to be freely moved. When the lever 35 is moved to the dotted line position, Fig. 4, the escapement button *g* is not actuated by a pull on the cord 22, and the carriage is returned in the customary manner without disengaging the rack and escapement mechanism.

In Fig. 6 I have shown a modification in lieu of lever 35 on the end of the arm 30^a. In this form I secure to the arm 30^a a short cylinder 37 having a notch 38 therein. Loose within this cylinder is a smaller sleeve 39 provided with a pin 40 arranged to enter the slot or notch 38. Screwed into the sleeve 39 is a screw 41 having a head 42, and on the screw is a spring 43 included between its head and a washer 44, said washer abutting against the end of the cylinder 37. As shown in Fig. 6, the pin 40 rests against the right hand edge of cylinder 37 and holds the screw 41 in position to engage the button *g*. By rotating the sleeve 39 so that the pin 40 will be opposite the slot 38, the spring 43 will draw the pin 40 into said slot or notch and permit the screw 41 to move away from button *g* a distance sufficient to prevent engagement therewith when the cord 22 is drawn. By rotating the screw 41 it can be adjusted to project to a greater or less extent from sleeve 39, so as to compensate for slight differences in the position of the button *g* on different typewriters.

In order to brace the upper part of the frame 1, Fig. 7, I provide a brace 45, Fig. 1, extending between a portion of the frame 55 of the machine and the extension 5, and preferably secured by or to the pin forming the stub shaft for pulley 20. This brace may be omitted if desired. In order to operate the machine in the customary manner the connection 26 may be removed from pin 27 and hooked over a hook 47 on the left hand end of the machine, shown in Fig. 1, whereupon the carriage-return mechanism is rendered inoperative, and the typewriter 65 may be operated in the customary manner.

The operation is as follows: In the drawings the carriage and the shifting mechanism therefor are shown in middle position. When the carriage is in its extreme right hand position, the lever 15 and the pinion 17 will be at the lower end of the rack 13. As the carriage moves to the left from the position shown in Fig. 1 the lever and pinion will gradually rise, and when the carriage has reached its extreme left position, the lever and pinion will be at the top of the rack, and to return the carriage it is only necessary to move the lever downward. The carriage may be shifted by means of the lever 15 from an intermediate position to either the right or left. When said lever is depressed, the cord 22 is tensioned, drawing the end 30^a of lever 30 to the right, thus causing the nose 36 of lever 35 to so move the button *g* that the escapement mechanism is rendered inoperative the same as when the button is pressed by a finger of the operator. The force of the spring, that operates to move the carriage to the left during the writing, now exerts a pull on the cord 22 tending to raise the lever 15. As long as the latter is held by the operator against the action of the spring, the escapement mechanism is inoperative and the carriage may be moved to the left by the force of said spring, by allowing the lever 15 to raise, or the carriage may be moved to the right by exerting sufficient pressure on the lever to overcome the force of the spring. When the carriage is being moved to the left, as above described, sufficient pressure must be constantly exerted on the lever to prevent the cord 22 from becoming slack, otherwise the escapement will operate to stop said movement. The carriage may be stopped during its movement in either direction at any desired point by suddenly releasing the lever 15. When the latter is released, the cord 22 becomes slack, the pressure of nose 36 on button *g* ceases, and allows the escapement mechanism to operate instantaneously, the same as when the button is released by the finger of the operator when the attachment is not employed. The carriage may be stepped forward by operating the lever 15 in the same manner as the space bar of the typewriter is operated. Should the carriage be moved by hand in the usual manner, instead of by lever 15, spring 16, whose hooked end 19 (Fig. 2) engages over one of the forks of lever 14, will have sufficient pressure on this lever to cause it to move down and take up the slack on cord 22 during this manual movement. If it is desired to move the carriage in one direction only, *i. e.*, to the right, and not permit its movement in the reverse direction, lever 35 is shifted to the position shown in dotted lines Fig. 4.

It is of course obvious that my planetary mechanism can be used not only for shifting

the carriage of typewriters, but may be used for shifting any movable carriage.

Claims:

1. In a typewriting machine, an escapement actuating member movable with the carriage, a flexible member connected with the actuating member, and means connected to the flexible member adapted to slacken and tension the latter to throw the actuating member into and out of operation respectively.

2. In a typewriting machine, an escapement actuating member movable with the carriage, a flexible member connected with the actuating member, and a pivoted lever connected to the flexible member adapted to slacken and tension the latter to throw the actuating member into and out of operation, respectively.

3. In a typewriting machine, the combination with an escapement disengaging device, of an actuating member for the latter, a flexible member connected with the actuating member, and a pivoted lever connected to the flexible member adapted to tension the flexible member to actuate the disengaging device and to slacken said flexible member to release said device.

4. In a carriage return mechanism for typewriting machines, the combination of means for engaging the carriage frame and escapement disengaging device of the typewriter, a rack, a pinion engaging said rack, a pulley connected to said pinion and a flexible connection connected at one end to said pulley and at the other end to said means, and means to cause the pinion to traverse the rack.

5. In a carriage return mechanism for typewriting machines, the combination with means for causing the disengagement of the typewriter escapement, of a stationary arcuate rack, a lever pivoted at the center of the rack, a pinion mounted on said lever for engagement with said rack, a cord pulley on said pinion, and a flexible connecting member connected at one end to said pulley and at the other end to said means.

6. In a carriage return mechanism for typewriting machines, a pivoted lever mounted on the typewriter carriage, and means on said lever arranged to actuate the escape-

ment disengaging mechanism, said lever pivoted to permit said means to move toward and from said mechanism and said means mounted on said lever to permit adjustment of said means into operative and inoperative positions.

7. In a carriage return mechanism for typewriting machines, an arm for attachment to the typewriter carriage, a lever pivoted on said arm, a sleeve on the end of said lever having a notch therein, a sleeve loose within said cylinder, a pin projecting from said sleeve, a screw in said sleeve and adapted to project therefrom, a spring to elevate said screw and sleeve when said pin is moved opposite said notch, and means on said lever for connection of an actuating cord.

8. In a carriage return mechanism for typewriting machines, a frame plate, an arcuate rack mounted thereon, a lever pivoted at the center of said rack, a pinion carried by said lever and meshing with said rack, a cord pulley on said pinion, a pivoted lever on the typewriting machine carriage, means on said lever movable into an operative and an inoperative position, for engaging the rack and escapement disengaging mechanism, and a cord extending along the typewriter carriage connected at one end to said cord pulley and at the other end detachably connected to said pivoted lever.

9. In a carriage return mechanism for typewriting machines, the combination with means for causing the disengagement of the typewriter escapement, of a stationary arcuate rack, a lever pivoted at the center of the rack, a pinion mounted on said lever for engagement with said rack, a cord pulley on said pinion, a flexible connecting member connected at one end to said pulley and at the other end to said means, and a spring acting on said lever to take up the slack in said cord when the carriage is manually returned.

In testimony that I claim the foregoing as my invention, I have signed my name in presence of two subscribing witnesses.

EDUARDO CASTAÑEDA.
